DISPLAY ATTACHMENT FOR AUTOMOBILES

Martin Marx and Walter Deutschmann,
New York, N. Y.

Application March 11, 1950, Serial No. 8,482

Term of patent 3½ years

(Cl. D14—6)

To all whom it may concern:

Be it known, that we, Walter Deutschmann and Martin Marx, citizens of the United States, residing in the county of New York and the State of New York, have invented a new, original, and ornamental Design for a Display Attachment for Automobiles, of which the following is a specification, reference being had to the accompanying drawing, forming part thereof.

Fig. 1 is a front view of a display attachment for automobiles showing our new design.

Fig. 2 is a side view.

Fig. 3 is a sectional view taken through a portion of the rim.

The characteristic features of our design reside in the portions shown by means of full lines in the drawing.

We claim:

The ornamental design for a display attachment for automobiles, substantially as shown and described.

MARTIN MARX.
WALTER DEUTSCHMANN.
